COMPENSATING LET-OFF MECHANISM

Filed March 1, 1930

UNITED STATES PATENT OFFICE

HARRY G. ROBINSON, OF WATERBURY, CONNECTICUT, ASSIGNOR TO INDUSTRIES OF AMERICA, INC., A CORPORATION OF DELAWARE

COMPENSATING LET-OFF MECHANISM

Application filed March 1, 1930. Serial No. 432,338.

This invention relates to appliances for controlling the delivery of yarn, thread or other articles of a similar character, such as wire and filaments, and is of particular utility when embodied in the construction of a supply carrier for braiding machines, although I contemplate the utilization of my improvements in any field for which they are adapted by nature.

An important object of this invention is to apply a constant tension of uniform character to the yarn, thread or wire as it is delivered from a supply carrier to a braiding machine or other mechanism in which the material is being used, the let-off arrangements being characterized by means for controlling them positively and with great sensitiveness, so that the supply may be fed quickly on demand while a uniform tension is maintained.

A clear conception of the operation, construction and other features of the invention may be had from the following specifications and claims, in conjunction with the accompanying drawing, in which:

Fig. 1 is a view in side elevation partially in section of a carrier adapted for use upon a braiding machine, in which the features of this invention are embodied.

Fig. 2 is a view at right angles to Fig. 1, certain parts being omitted for clearness of illustration.

Fig. 3 is a cross-section at 3-3 of Fig. 1.

Fig. 4 is a detailed vertical section of a part of Fig. 1, on a larger scale.

Fig. 5 is a schematic layout of the machine in which the invention is used.

In the now preferred form of carrier, the base 1 is a circular plate as shown adapted for use in a braiding machine similar to that described in my co-pending application for Letters Patent, Serial No. 137,395 filed September 24, 1926.

This base has a threaded bore 4, within which is screwed a post 5, having a head 6 which serves to hold in place a plate 7, carrying the filling supply B and the let-off mechanism is designated in general by L.

The filling supply B is shown as taking the form of a mass of yarn or thread wound upon a conventional paper bobbin or tube 8

within which extends a hollow shaft or cylinder 9, having an annular collar 2 fitted thereon. The use of this collar will be described hereinafter.

Within shaft 9 is a second hollow shaft 10, separated from shaft 9 at the bottom by a collar 11 and at the top by a similar collar 12. Hollow shaft 10 is mounted on head 6 in such a manner that it has a limited rotative movement under constraint by a spring 13, which is fastened in head 6 at the bottom and in a collar 14 at the top, the collar 14 acting as a spacing member between a dead spindle 15 and the hollow shaft 10. Both shafts 9 and 10 are held in vertical relation with spindle 15 by means of a washer 16 and cotter pin 17. Forced on to the bottom of shaft 10 is a circular plate 20, on which is mounted a post 19 carrying a part of the let-off mechanism.

Shaft 10 has a movement to and fro about spindle 15 under control of spring 13 and shaft 9 is free to rotate with bobbin 8 and the thread mass B about shaft 10 as an axis. The operation of these parts will be explained hereinafter.

The let-off mechanism illustrated comprises an eye 18 formed in the top of the post 19, from which extends upward a guide wire 21, having an eye 22 formed in its top.

Post 19 has an axially movable collar or rider 23 mounted thereon and normally pressed downward by a spring 24, this rider 23 having a guide eye 25 formed on one side.

The plate 7 has two split arms 26, formed thereon, in which is mounted a wire frame 27 shaped as shown in Figs. 1 and 2 with a guide eye 32 formed in its uppermost part.

A cross bar of wire having an eye 28 in its center portion is spot-welded to frame 27 as shown, and a second bar having an eye 29 in its center portion is welded nearer the top of frame 27. A third cross bar 30 is welded to the frame between the eyes 28 and 29, this bar supporting a socket 31 for holding a column 33, which extends upward from an arm formed on plate 7, as shown, having a socket or supporting member 34 for the column 33.

The socket 31 constitutes the upper jaw 100

of a clamping device through which the yarn or thread is run, and has pegs 35, as shown in Fig. 2, which form a guide for the thread. Hinged to the upper jaw is a lower jaw 36, which is normally pressed against the upper jaw 31 by means of spring 37, the tension of which may be adjusted by collar 38 held to column 33 by set screw 39. Jaw 31 also forms a guide or bearing for a lever arm 40, which 10 has a rocker-shaped part 41, and a hook 42 at its free upper end.

Attached to arm 40 by a hook 43 is a tension spring 44, which is fastened at its other end by hook 45. The operation of this spring 15 will be explained hereinafter.

Passing through the upper jaw 31 is a pin 46, which is in engagement with lower jaw 36, and is of sufficient length to be engaged and depressed by foot 41 when the arm 40 20 is raised against the tension of spring 44.

When arm 40 is in a position nearly vertical, the part 41 depresses pin 46 and forces jaws 36 away from jaw 31 compressing spring 37, thereby releasing the grip on the 25 thread.

A detector member 47 may be provided for detecting broken threads, and is composed of a piece of wire having an eye 48 in its upper end, and which passes through an eye 49 in 30 the collar 38, and thence through a bearing in socket 34 which is cut away at 50 to form an open space in which a wire 51 may move. Wire 51 is spot-welded to member 47 and to a pin 52, which is free to move up and down 35 in a bearing in plug 5. This pin may be used to trip a lever, thereby stopping the braiding machine when the thread breaks or to make an electrical contact for giving an alarm, for example as described and claimed in my co- 40 pending application Serial No. 117,904, filed June 23, 1926.

The circular plate 2, already mentioned, has on its periphery a series of ratchet teeth, such as those illustrated at 54, adapted to be 45 engaged serially by a projection 3 on the rider 23 already described.

Plate 2 revolves with the bobbin B. The thread 55 is taken off the bobbin B through eye 18, and then is drawn down and through 50 eye 25, and passes thence through eyes 22 and 28 to the jaws 35 and 36 of the gripping device. The thread is then carried through eye 48 of detector bar 47, thence through eye 29 to the hook 42 on arm 40, and thence through 55 eye 32 to the braiding point.

As the thread is pulled taut the arm 40 is moved toward a vertical position, thereby depressing pin 46 and opening jaws 31 and 36, releasing the grip on the thread 55 and 60 allowing it to move freely, until the tension is sufficient to pull the rider 23 up against the action of spring 24. When the rider 23 has been raised sufficiently it moves the projection 3 upward, out of the path of the teeth 54, and thus releases the nearest tooth 54, 65

thereby allowing the bobbin B to revolve, and let off a supply of thread.

As the tension on thread 55 is released the arm 40 is drawn down by means of spring 44, thereby keeping the thread taut between eyes 29 and 32, and the foot 41 on arm 40 releases pin 46, allowing jaws 31 and 36 to tighten their grip on the thread, and thereby hold it taut. The tension being released on the thread between eyes 28 and 25 the rider 23 70 is forced down by spring 24, thereby tightening the thread between the jaws 31 and 36 and eye 18, and causing the bobbin to revolve. 75

If the tension is released sufficiently to 80 allow rider 23 to drop to the bottom of shaft 19, projection 3 will engage one of the teeth 54, thereby stopping the rotation of the bobbin B within a short distance.

It will be seen, therefore, that bobbin B will not feed more thread until the tension 85 on thread 55 is sufficient to cause arm 40 to release jaws 31 and 36, and raise rider 23 out of engagement with one of the teeth 54. It is apparent therefore that this device will 90 provide thread, yarn or wire to the machine at a constant tension.

A plan view of the rotating driver discs of a braiding machine described in the above first mentioned application, is shown in Fig. 5. As the operation of these discs is described in detail in this application, it will 95 only be necessary to say that the plate 1 of the supply carrier is grasped by the rotating driver disc 60 and transferred to disc 61, thence to disc 62 etc., until 67 is reached. Each 100 of these discs rotate in the direction indicated by the arrow. It is apparent, therefore, that the carrier moves in a sinuous path, first being rotated in one direction and then in another. Disc 67 reverses the direction and starts the carrier back over a similar sinuous route. While following these paths, the carrier picks up considerable centrifugal motion, which, if in the feed-off direction, will 105 cause the bobbin B to rotate faster than is necessary to provide taut yarn to the braider. This will cause a slack which will allow the let-off mechanism to operate as described above, and rider 23 will fall and engage one 110 of the teeth 54 on disc 2 thereby stopping the rotation of bobbin B. This stop, which is necessarily abrupt, creates a danger of snapping the thread 55. This danger is overcome by means of spring 13 which is in co-operation with hollow shaft 10 as described 115 above. The disc 20 which carries rod 19 and rider 23 is attached to shaft 10 which is capable of rotating until the limit of spring 13 is reached. It is clear that the mechanism of bobbin B will cause the plate 20 to rotate through the medium of rider 23. When the limit of spring 13 is reached and the centrifugal force dissipated, the plate 20 will be rotated in a reverse direction, the retarded oscillation caused thereby taking up 120

125

130

the shock of the sudden stop and obviating the danger of snapping the thread 55.

I claim:

1. In a thread carrier for sinuous path 5
braiding machines, a carrier base, a thread support mounted rotatably thereon, means to regulate rotation of said support relatively to said base, for delivery of thread, and means to facilitate oscillating rotative movement of said base relatively to said thread support during its progress through a sinuous path without corresponding rotative movements of said thread support. 10

2. In a thread carrier for sinuous path 15
braiding machines, a carrier base, a thread support mounted rotatably thereon, means to regulate rotation of said support relatively to said base, for delivery of thread and a spring to oppose yieldingly the oscillation of said thread support caused by rotative movement of said base in either direction relatively to said thread support during its progress through a sinuous path and thereby to control corresponding rotative movements 20
25 of said thread support.

3. In a thread carrier for sinuous path 30
braiding machines, a carrier base, a thread support mounted rotatably thereon, means to regulate rotation of said support relatively to said base, for delivery of thread and means to oppose yieldingly the oscillation of said thread support caused by rotative movement of said base in either direction relatively to said thread support during its progress 35 through a sinuous path and thereby to control corresponding rotative movements of said thread support.

4. In a thread carrier for sinuous path 40
braiding machines, a carrier base, a thread support mounted rotatably thereon, a let-off mechanism comprising frictional means adapted to act directly upon the thread from said support to retard withdrawal thereof, a tension device to take up slack in the thread delivered from said retarding means, a connection between said tension device and retarding means to insure delivery of the supply under constant tension, means whereby the forward feeding rotation of said thread support relatively to said base is retarded variably as the draft upon the thread varies, and means to facilitate oscillating rotative movement of said base relatively to said thread support during its progress through 45
50 a sinuous path without corresponding rotative movements of said thread support.

5. In a thread carrier for sinuous path 55
braiding machines, a carrier base, a thread support mounted rotatably thereon, a let-off mechanism comprising in part a pawl member adapted to be raised and lowered as the draft on the thread from said support varies; a circular plate secured to said thread support with teeth thereon for co-operation with said pawl member, said pawl and teeth

holding said thread support from rotating with relation to said let-off when the draft on said thread is lessened, and means to oppose yieldingly the oscillation of said thread support caused by rotative movement of said base relatively to said plate during its progress through a sinuous path and thereby to control corresponding rotative movements of said plate, and tending constantly to restore said plate to a predetermined normal position relatively to said base. 70
75

6. In a thread carrier for sinuous path 80
braiding machines, a carrier base, a thread support mounted rotatably thereon, a let-off mechanism mounted on said base comprising in part a pawl member adapted to be raised and lowered as the draft on the thread from said support varies; a circular plate secured to said thread support with teeth thereon for co-operation with said pawl member, said pawl and teeth holding said thread support from rotating with relation to said let-off when the draft on said thread is lessened, and means to oppose yieldingly the oscillation of 85
90 said thread support caused by rotative movement of said base relatively to said thread support during its progress through a sinuous path and thereby to control corresponding rotative movements of said thread support.

7. In a thread carrier for sinuous path 95
braiding machine, a carrier base, a let-off mechanism comprising in part a post mounted on a circular plate which is mounted on a hollow shaft, said shaft being free to rotate on said base, a second hollow shaft carrying a thread support positioned there between and fastened to said base and first shaft, a circular plate having teeth thereon secured to said second shaft, said post having a pawl member mounted slidably thereon adapted to be raised and lowered as the draft on the thread from said support varies, said pawl and teeth co-operating to hold said thread support from rotating with respect to said first shaft and a spring acting on said first shaft to facilitate a limited oscillatory rotative movement of said first shaft with respect to said base, and tending constantly to restore said plate to a predetermined normal rotative position relatively to said base. 100
105
110
115

In testimony whereof, I have signed this specification.

HARRY G. ROBINSON.
